Frank L. Rosenthal

By his Attorney. T. H. Alexander.

UNITED STATES PATENT OFFICE.

FRANK L. ROSENTRETER, OF CLEVELAND, OHIO, ASSIGNOR TO THE ANDRUS MANUFACTURING COMPANY, OF ROCHESTER, NEW YORK.

SASH-HOLDER.

SPECIFICATION forming part of Letters Patent No. 379,664, dated March 20, 1888.

Application filed June 6, 1887. Serial No. 240,356. (No model.)

To all whom it may concern:

Be it known that I, FRANK L. ROSENTRETER, of Cleveland, in the county of Cuyahoga and State of Ohio, have invented certain new and useful Improvements in Window-Sash Fasteners; and I do hereby declare that the following is a full, clear, and exact description thereof, reference being had to the accompanying drawings, and to the letters of reference marked ⁵ to thereon, which form part of this specification, in which—

Figure 1 is a side view of my improved sash-lock applied for use and closed. Fig. 2 is a similar view of the lock open. Fig. 3 is a horizontal section on line $x-x$, Fig. 1. Fig. 4 is a similar section on line $y-y$, Fig. 2. Figs. 5, 6, 7, and 8 are details.

This invention relates to improvements in sash locks or fasteners; and it has for its objects to provide a lock in which the engaging-plate will be quickly moved initially before its locking devices are engaged, and also to simplify the construction of the lock.

The invention consists in the peculiar and ²⁵ novel construction and arrangement of the component parts of the lock, hereinafter described, illustrated in the drawings, and particularly specified in the claims hereto appended.

Referring to the drawings by letter, W designates a window-sash, to a proper point on one side of which is secured my improved lock. This lock is composed of a base supporting-piece, A , a sliding engaging-plate, E , and ³⁵ an actuating cam-piece, I , which are constructed as follows: Piece A consists of a rectangular block, a , which is made hollow for lightness, and which has at its ends the perforated ears B for the passage of proper retaining-screws, by which the base-piece A is secured, as shown, to a window-sash. The ears B are provided with rearward extensions, b , for the purpose of preventing rocking or lateral turning of base-piece A . On top of block a are formed two upstanding ribs, $C C$, which extend rearward a short distance, and their rear ends converge, as shown, for a purpose hereinafter explained. On the under surface of block a is formed a semicircular groove, D , ⁴⁰ and near the rear end of one rib C , on its lower surface, is a lug, d , hereinafter referred to.

The engaging-plate E consists of a rectangular hollowed shell, e , which is adapted to fit and move longitudinally over the ribs C of base-piece A , the side walls of the shell e being properly reduced, as shown. At the front edge of shell e is the binding plate or edge F , and near its rear end is an upstanding pin, G , the lower sides of which are squared and form part of a guide rib or ribs, g , which extend ⁵⁵ from said pin to the rear end of shell e and are hereinafter referred to. At the front of shell e , and extending rearward nearly to pin G , are formed two parallel ribs, H , which are arranged a distance apart corresponding to ⁶⁰ the ribs $C C$ of base-piece A , by which latter they are embraced and engaged, so as to guide engaging-plate E in its movements over base-piece A . The ends of ribs $C C$ converge, as ⁶⁵ described, and are adapted to embrace and engage the ribs g , so that the engaging-plate E will be steadily and firmly guided on base-piece A .

The cam-piece I consists of a concentric disk, i , from which extends a proper handle, J . ⁷⁰ This disk i is centrally perforated, and is adapted to be placed upon and loosely riveted by pin G , thereby securing the cam-piece I to engaging-plate E . On the upper surface of disk i are formed the pair of lugs $K k$ and the convolute-bend cam L , which extends from a point near the pivot of the disk to a point near the periphery of the same about diametrically opposite its starting-point. The lugs $K k$ are on the diametrically-opposite side of the pivot of ⁷⁵ disk i from cam L , and the lug K is elongated, as shown, for a purpose hereinafter explained.

To put the lock together, engaging-plate E is placed upon base-piece A , so that their respective ribs H and C engage, as described, ⁸⁰ and base-piece A is slid toward the rear end of engaging-plate E until its movement is stopped by pin G . When thus placed, the groove D in base-piece A will be concentric to pin G , and the lug d also lies in close relation ⁸⁵ thereto. The cam-piece I is then placed on pin G and turned until its cam L engages in groove D , and is then riveted on pin G . When thus adjusted, the parts stand in the position shown in Fig. 1, and cam L has passed partially out of groove D , and the lugs $K k$ are entirely removed from lug d . The parts are then ⁹⁰ ⁹⁵ ¹⁰⁰

in locking position, and to retract the engaging-plate E the cam-piece I is retracted. This movement causes the outer edge of cam L to bind against the outer edge of groove D and 5 move the engaging-plate E inward, this action continuing until cam L disengages groove D. Simultaneously with the disengagement of the cam and groove the lugs K k embrace and engage the lug d, and the lug K, owing to its 10 distance from the center, causes a more rapid retraction of the engaging-plate E through lug d, as is evident, than was effected by cam L. Similarly, upon throwing the engaging-plate E forward by turning disk i the lugs K k first 15 engage with lug d and start the engaging-plate E forward rapidly for a short distance, when they disengage, and the cam L, by its inner face, simultaneously engages against the inner wall of groove D, and more slowly but power- 20 fully moves the engaging-plate E forward. The situation of the cam L in relation to its pivot on engaging-plate E and engagement with base-piece A is such that pressure ex- 25 erted upon the binding-plate F, and from thence to base-piece A, through cam L and groove D, will be in a direct line taken from the pivot-pin G through the cam and its point of engagement with groove D, so that after the cam L has engaged said groove the locking 30 35 can be at once effected without necessitating the full movement of the handle J.

It will be observed that the cam-piece I is pivoted upon and consequently moves with the engaging-plate E, while the base-piece A only 35 is stationary; and by thus arranging the parts the engaging-plate E forms the cover or outer portion of the lock, and can be made highly ornamental and of varying forms without ef- fecting its working, and, further, that all the 40 working parts of the lock are protected, and no unsightly riveting necessary, and that the engaging-plate E is entirely exposed to view both when locked or unlocked. It will fur-

ther be observed that by arranging the lugs K k farther from or nearer to the center of disk i a greater or less amount of quick initial movement can be imparted to engaging-plate E before the cam L is engaged. 45

The handle J is bent, as shown, so that when the lock is retracted its upper end stands 50 almost horizontal and its part j abuts against the upper end of base-piece A. The handle thus forms a convenient and ornamental knob or finger-piece by which the sash can be ele- 55 vated or lowered.

Having described my invention, I claim—

1. In a sash-lock, the combination of a sup- 60 porting fixed base-piece, A, secured to the win- dow-sash and provided with extended guide- ribs on its outer surface and with a semicircu- lar groove on its under surface, with a sliding engaging-plate, E, fitting over the fixed piece and provided with ribs engaging with the ribs 65 thereof, and having pin G at its rear end and a binding-plate on its front end, and a cam- piece pivoted upon the pin G below the ex- tensions of the ribs of base-piece A, and hav- 70 ing a cam, L, engaging in the groove of said base-piece, all constructed and arranged sub- stantially in the manner and for the purpose 75 described.

2. In a sash-lock, the combination of the 75 base-piece A, having groove D and lug d, and extended ribs C C, with the engaging-plate E, having ribs H g and pin G, and the cam-piece I, pivoted upon pin G and having the lugs K k, adapted to engage lug d, and cam L, for en- gaging groove D, all constructed and arranged substantially as and for the purpose described.

In testimony that I claim the foregoing as 80 my own I affix my signature in presence of two witnesses.

FRANK L. ROSENTRETER.
